CLAIM

The ornamental design for a sport bar as shown and described.

DESCRIPTION

FIG. 1 is a perspective view of the sport bar showing my new design;

FIG. 2 is a top view thereof;

FIG. 3 is a right side view thereof;

FIG. 4 is a left side view thereof;

FIG. 5 is a back view thereof;

FIG. 6 is a front view thereof; and,

FIG. 7 is a bottom view thereof.

In the drawings, broken lines depict portions of the sport bar that form no part of the claimed design.
